UNITED STATES PATENT OFFICE

2,446,593

AIR CONDITIONING SYSTEM

Sam C. Jimopoulos, St. Louis, Mo.

Application December 16, 1943, Serial No. 514,552

4 Claims. (Cl. 98—31)

1

The present invention relates to air conditioning of houses, and more particularly to a system for supplying the rooms of a house with fresh wholesome air in a manner to reduce the room temperature in summer and to ensure increased heating efficiency in winter. The system applies to houses having air heating furnaces in the basements, as well as to houses having stove heat, and both of these arrangements will be described herein.

My invention is fully described in the following specification and illustrated in the accompanying drawings, wherein like reference characters indicate corresponding parts throughout the several views.

In the accompanying drawings:

Figure 1 is a horizontal section through the rooms on the first floor of a house having a hot air furnace in the basement, radiating air outlet conduits being extended from the furnace jacket.

Figure 2 is a vertical section taken on line 2—2 of Figure 1.

Figure 3 is a fragmentary vertical section taken on line 3—3 of Figure 1, and showing the basement wall of Figure 2.

Figure 4 is a fragmentary section of a basement corner, wherein hollow tiles are used to form air flues in the walls of the basement.

Figure 5 is a front view, partly in section, showing the hollow tile wall construction provided with an air choke or baffle and a partition for dividing the air ducts or flues and changing the direction of air flow to the furnace.

Figure 6 is a fragmentary elevation showing a modification of the basement wall constructed of hollow tile and having air ducts, the direction of air flow being indicated by arrows.

Figure 7 is a view partly in elevation and partly in section, more clearly showing the partition arrangement of Figure 5.

Referring first to the embodiment of Figures 1 to 7, inclusive, Figure 1 shows the first floor plan of a house having several rooms on the floor, as indicated at A, B, C, D and E, respectively. Beneath room A, in the basement, is located a hot air furnace 15 which has the usual jacket 16 from which radiate several air supply pipes 17 for air distribution to the different rooms on the first floor. Cold air from the first floor is collected through respective grated floor registers 19 which have cut-off shutters 19' and which communicate through suitable pipes, as shown in Figure 2, with vertical channels 20 running down from near-the-ceiling vents 21 and opening into the horizontal passages 22 in the porous hollow tiles

2

23 of which the basement walls are constructed. The vents 21 have cut-off shutters 21'. The basement walls are erected on a concrete floor 36 and have an outside layer 24 of concrete and an inside lining 25 of cement. The tiles are laid with their passages 22 aligned and continuously running horizontally so as to open into a metal coping 26 forming an air inlet to the jacket 16 of furnace 15. In the coping 26 is mounted a fan blower 27 which draws air in through the near-the-ceiling vents 21, or through floor vents 19 which open into the vertical channels 20, and then through the horizontal tile passages of the basement walls into the coping 26. The fan blower 27 discharges this air into the furnace jacket 16 after having been cooled and moistened in its circuit around the building, and the air is then returned to the rooms through the pipes 17 and wall registers 18.

20 Below the channel 20 which is located nearly opposite or most remote from the furnace, the tiling is provided with a vertical partition 30 in order to divide the air intake to the furnace from both sides, as indicated by the oppositely directed arrows in Figures 5 and 7. An air duct arrangement for equalizing the lengths of air flow is seen in Figure 6, where arrows indicate the directions of air flow. This arrangement is provided where a partition P is provided between adjacent rooms and air channels 20a extend downwardly from near-the-ceiling vents at opposite sides of said partition P. It will be noted that the air flows from the channels 20a into upper ducts of the adjacent portion of the tile wall for flow in a direction away from the furnace until it reaches the partition 30 in said wall for being subsequently returned in the opposite direction through the lower ducts of said wall portion to the furnace.

35 40 In Figure 5 is shown still another manner of equalizing the length of air flow, wherein an air choke 29 is provided between sections of the wall beneath a channel 20 located near the furnace. The choke 29 consists of a diagonally placed plate for diverting the air from channel 20 in a direction away from the furnace through the upper ducts of a portion of the tile wall, for being subsequently returned in the opposite direction through the lower ducts of said wall portion after reaching the partition 30 of Figure 5 or 7.

45 50 In the operation of this embodiment of the invention, air is drawn from adjacent the ceiling through the near-the-ceiling vents down through the wall channels 20, through the hollow porous tiling to coping 26, and is then forced into the

furnace jacket 16 for being subsequently expelled through the pipes 17 and wall registers 18. This operation is followed in summer, the shutters 21' of vents 21 being open, and the shutters 19' of registers 19 being closed. In winter the operation is the same, except that the shutters 21' of vents 21 are closed and shutters 19' of registers 19 are opened, thereby causing the air to be drawn from the rooms at the floor instead of from near the ceiling. In summer, the furnace is of course not in operation, but in winter it is in operation so that the system serves as a heat booster.

From the foregoing description, it is believed that the various embodiments, as well as the operation thereof, will be readily understood, and the advantages thereof appreciated. Other modifications will suggest themselves to those skilled in the art.

What I claim is:

1. In an air conditioning system for a house having rooms above the level of the surface of the ground and a basement below said level, basement side and end walls of concrete below said level, basement inner side and end walls formed of vertical rows of porous tiles laid adjacent to the concrete walls, the tiles having through passages extending lengthwise of the walls and laid end to end to form continuous elongated conduits one above the other, there being a vertical outlet passageway in one of said tile walls into which passageway some of the conduits open, said outlet passageway leading into the house above the basement, a vertical inlet passageway in another of said tile walls opposite said first-mentioned wall and into which inlet passageway other conduits open, said inlet passageway leading from the interior of the house above the basement, a central vertical partition in said inlet passageway dividing incoming air and directing it in opposite directions into conduits opening into opposite sides of the inlet passageway and leading therefrom to the outlet passageway, other similarly leading vertical inlet passageways formed in said tile wall at spaced intervals along the perimeter of the basement, a diagonal baffle in each of said last-mentioned inlet passageways extending from one side of the top of the passageway to a lower portion of the opposite side for directing incoming air to the upper conduits of said tile wall, said upper conduits leading to said first inlet passageway where the air is directed by said partition to the lower conduits leading, beneath said diagonal baffle, to the outlet passageway.

2. In an air conditioning system for a house having rooms above the level of the surface of the ground and a basement below said level, basement side and end walls of concrete below said level, basement inner side and end walls formed of porous tiles laid adjacent to the concrete walls, the tiles having through passages extending lengthwise of the walls and laid end to end to form continuous elongated conduits one above the other, there being a vertical outlet passageway in one of said tile walls into which passageway some of the conduits open, said outlet passageway leading into the house above the basement, a vertical inlet passageway remote from said outlet passageway and into which inlet passageway other conduits open, said inlet passageway leading from the interior of the house above the basement, a central vertical partition in said inlet passageway dividing incoming air and directing it in opposite directions into conduits opening into opposite sides of the inlet passageway and leading therefrom to the outlet passageway, additional

vertical similarly leading inlet passageways formed in said tile wall at spaced intervals between said outlet passageway and said first-mentioned inlet passageway, a diagonal baffle in each of said additional passageways each extending from the top of one side of the passageway with its lower portion at the opposite side of the passageway for directing incoming air to the upper conduits opening to one side of the passageway, said upper conduits leading to said first inlet passageway where the air is directed by said partition to the lower conduits leading back beneath said diagonal baffle to the outlet passageway.

3. In an air conditioning system for a house which includes rooms above the level of the surface of the ground and a basement below said level, a basement wall including porous tiles, the tiles having through passages extending lengthwise of the wall and arranged end to end so that said passages form a plurality of parallel elongated conduits one above the other and each of relatively restricted vertical cross sectional area, compared to the vertical cross sectional area of the wall, a vertical inlet passageway in said tiles connecting adjacent ends of all of the conduits intersected by the passageway and there being an upright partition in said passageway spaced from and opposing said ends, another vertical inlet passageway in the tiles connecting adjacent ends of all of the conduits intersected thereby, a partition in said last-mentioned vertical passageway extending diagonally downwardly from one side of the top of the passageway to a portion of the opposite side of the passageway intermediate the top and bottom thereof for directing air received through said last-mentioned inlet passageway into the upper conduits of the tiles at one side of said latter-mentioned passageway and directing air delivered from the lower conduits of said tiles into all the conduits at the opposite side of said latter-mentioned conduits back to a house room, there being fan-like means for moving air in the system from the house rooms through said passageways and all said conduits between said passageways, and back to the house rooms.

4. In an air conditioning system for a house which includes rooms above the level of the surface of the ground and a basement below the surface, a basement wall including a layer of porous tiles below said level and adjacent the ground substantially throughout the depth of the basement, said tiles having through passages arranged horizontally and in line end to end so that said passages form a plurality of parallel elongated horizontal conduits one above the other and each of relatively restricted vertical cross sectional area, compared to the vertical cross sectional area of said layer and extending throughout a major portion of the length of said layer and having open ends, a vertical inlet passageway in said layer leading from one of the house rooms and opening into approximately half of said elongated conduits, another vertical passageway in said layer remote from said first-mentioned passageway and opening into all of said conduits, an outlet passageway in said layer adjacent said first-mentioned passageway and connected to the remaining half of said conduits, a passageway leading from said outlet passageway to one of the house rooms, and a fan-like device associated with one of said passageways, for moving air from the house through said inlet passageway to certain of said conduits, then to said 75 remote vertical passageway, then to the remain-

der of said conduits and from the same to said outlet passageway and to the house.
